STICK TOY

Arthur W. Frisk, South Bend, Ind.

Application March 1, 1957, Serial No. 45,044

Term of patent 14 years

(Cl. D34—15)

Fig. 1 is a perspective view of a stick toy, showing my new design;

Fig. 2 is a side elevational view, to a reduced scale;

Fig. 3 is a fragmentary front elevational view, a portion of the stick being omitted for convenience in illustration; and

Fig. 4 is a fragmentary front elevational view thereof to an enlarged scale, partly in cross-section taken on line 4—4 in Fig. 2, a portion of the stick being omitted for convenience in illustration.

I claim:

The ornamental design for a stick toy, as shown and described.
